GEORGE D. CLARK, OF PLAINVILLE, CONNECTICUT, ASSIGNOR TO HIMSELF AND CLARK AND COWLES, OF SAME PLACE.

Letters Patent No. 80,710, dated August 4, 1868.

IMPROVEMENT IN FASTENINGS FOR BUTTONS.

The Schedule referred to in these Letters Patent and making part of the same.

TO ALL WHOM IT MAY CONCERN:

Be it known that I, GEORGE D. CLARK, of Plainville, in the county of Hartford, and State of Connecticut, have invented a new Improvement in Button-Fastener; and I do hereby declare the following, when taken in connection with the accompanying drawings and the letters of reference marked thereon, to be a full, clear, and exact description of the same, and which said drawings constitute part of this specification, and represent, in—

Figure 1, an upper side view of the fastening.

Figure 2, a sectional view, and in

Figures 3 and 4 the manner of fastening.

This invention relates to an improvement in securing to garments that class of buttons which are formed with an eye or loop as a means by which to secure the button, the object being to attach the button so firmly that it cannot be accidentally detached; and the invention consists in the construction of a plate or washer so as to permit the insertion of the eye through the said washer after it has passed through the garment, then two points raised upon the washer in its formation are turned down, so as to enter the eye, and thus lock or secure the button to the garment.

To enable others to fully understand my invention, I will proceed to describe the same as illustrated in the accompanying drawings.

A, as seen in fig. 1, is a plate struck from suitable sheet metal, and of any desired form or configuration, having a slot, *a*, punched through its centre, so as to permit the free passage of the button's eye therethrough. At the centre, upon one or both sides, a portion of the plate, as at *d*, is turned up, as in fig. 2, instead of being cut away at each side, and the said raised part left, so that, when pressed back into a plane with the plate, a bridge will be formed across the central slot.

This finishes the construction of the fastener. Its use is as follows: Place the button B through the garment, as denoted in fig. 4; then place the plate A over the eye, as also seen in fig. 4; then, with a suitable instrument, strike the raised portion, *d*, down, which operation causes the said raised portion to pass into and through the eye, as denoted in fig. 3.

I prefer to make the raised portion alike upon opposite edges of the slot, but it may, if preferred, be formed entirely upon one edge.

This fastener is peculiarly adapted to securing buttons to shoes, but is alike applicable to securing buttons with eyes for other purposes.

Having thus fully described my invention, what I claim as new and useful, and desire to secure by Letters Patent, is—

The herein-described button-fastener, as an article of manufacture, consisting of the plate A, with the slot *a*, and one or more projections, *d*, substantially as set forth.

GEO. D. CLARK.
